UNITED STATES PATENT OFFICE.

HARRY DERMAN, OF BRONX, NEW YORK.

TIE CORD FOR CONTAINERS.

Application filed June 9, 1923. Serial No. 644,322.

To all whom it may concern:

Be it known that I, HARRY DERMAN, a citizen of the United States, and residing at Bronx, in the county of Bronx and State of New York, have invented certain new and useful Improvements in Tie Cords for Containers, of which the following is a specification, such as will enable those skilled in the art to which it appertains to make and use the same.

This invention relates to improved means for attaching tie cords of various kinds and classes in connection with boxes or other containers as well as for securing retaining strips or straps in connection with such articles, and the object of the invention is to provide a simple, effective, strong and durable means for attaching strings, cords, straps or the like to containers of various kinds and classes; and with this and other objects in view the invention consists in the herein-after described and claimed means for carrying my invention into effect.

The invention is fully disclosed in the following specification, of which the accompanying drawing forms a part, in which the separate parts of my improvement are designated by suitable reference characters in each of the views, and in which:—

Fig. 1 is a perspective view of a box showing a number of tie cords attached thereto and indicating the method of their use part of the construction being broken away and in section;

Fig. 2 is a partial section on the line 2—2 of Fig. 1; and,

Fig. 3 is a sectional view through a modified form of container showing a retaining strip mounted in accordance with my invention.

In Figs. 1 and 2 of the drawing, I have shown for the purpose of illustrating one method of carrying my invention into effect, a box 5 comprising a bottom member 6 and side and end walls 7, the box 5 is open at the top and adapted to be closed by a cover 8 in the usual or any desired manner.

In boxes of the class under consideration and used as containers, it is customary to attach cords, tapes or the like thereto by either perforating the box, by gluing, sewing or otherwise attaching these tie cords or straps.

My invention consists in attaching to the outer faces of the side or end walls 7 of the box one end portion of strap members 9 by the use of one or more staples 10 so that

when the cover 8 is placed upon the box 5 the side and end walls 8^a of the cover conceal the staples 10, and the free end portions of the strap members 9 are extended upwardly around the cover and are tied together to retain the cover 8 in connection with the box 5.

If desired, these straps may be both of the same length or one may be shorter than the other so that they may be tied at any desirable point but, in the construction shown, the straps 9 both are of substantially the same length.

By securing the straps 9 or any other members of this kind to containers of various kinds and classes, said straps may be quickly and simply attached to the container or any part thereof, and yet securely held in connection therewith, thus avoiding the expense in producing containers with said members as has heretofore been the custom by providing apertures in the container and threading a long strap member therethrough or by gluing or stitching short strap members to the containers. With my invention, however, I not only simplify the method of attaching the strap members but also save in the material used as strap members thus as a whole materially reducing the cost of producing the entire box.

I may also secure other strap members 11 to the inner faces of the walls 7 of the box to be used for retaining garments, fabric or the like 12 within the container in predetermined position, and the strap members 11 may be secured by the same staples 10 passed through the strap members 9, or may be separately secured by the use of other staples, if desired, but in the construction shown I have illustrated these strap members secured together by the one staple or, in other words, secured together in one operation by passing the staple through the box member by the use of a suitable machine or device for this purpose. It will also be understood that the central portion of one strap member may be secured in the manner shown in Fig. 1 of the drawing and the free ends allowed to extend outwardly and inwardly of the box at the opposite sides thereof, and this method of procedure is indicated in Fig. 2 of the drawing.

In Fig. 3 of the drawing, I have shown a box or container 5^a having a cover member 13 movably connected with one side thereof by a hinge structure 14 and in said figure I

have shown a strap member 15 which is designed to support the cover member 13 in an open position, and, in practice, I attach the end portions of the strap members 15 to the box 5^a and to the cover member 13 by staples 16 in the same manner as attaching the straps 9 and 11 to the box 5 as shown in Figs. 1 and 2 of the drawing.

From the foregoing it will be apparent that my invention is not limited to the securing of strap members to any specific container nor am I necessarily limited to attaching, what I term, tie cords or straps to such container, as I may attach and secure strings, cords, straps, tapes or the like to any kind or class of a container, and for any purpose, and various changes in and modifications of the construction herein shown and described may be made, within the scope of the appended claims, without departing from the spirit of my invention or sacrificing its advantages.

Having fully described my invention what I claim as new and desire to secure by Letters Patent, is:—

1. A box of the class described comprising a box member proper and a cover member, the side walls of said box member being provided with tie cords secured thereto by one or more staples, the attached end portions of said tie cords being located within the side walls of the cover member and the free end portions of said tie cords being adapted to extend outwardly, upwardly and around said cover member for securing the same to the box member.

2. In a box of the class described, a box member and cover member, and tie cords secured to the outer faces of the side walls of the box member adjacent to the upper edges thereof by one or more staples the attached ends of said cords being concealed within the walls of the cover member when said cover member is mounted in connection with the box member.

3. In a box of the class described, a box member and cover member, tie cords secured to the outer faces of the side walls of the box member adjacent to the upper edges thereof by one or more staples the attached ends of said cords being concealed within the walls of the cover member when said cover member is mounted in connection with the box member and said tie cords being adapted to extend outwardly, upwardly and around the cover member for securing the same to said box member.

4. In a box of the class described, a box member and cover member, tie cords secured to the outer faces of the side walls of the box member adjacent to the upper edges

thereof by one or more staples, said tie cords being adapted to extend outwardly, upwardly and around the cover member for securing the same to said box member, and the attached ends of said tie cords being located within and concealed by the side walls of the cover member.

5. In a box of the class described, a box member and cover member, tie cords secured to the outer faces of the side walls of the box member adjacent to the upper edges thereof by one or more staples, said tie cords being adapted to extend outwardly, upwardly and around the cover member for securing the same to said box member, the attached ends of said tie cords being located within and concealed by the side walls of the cover member, and other tie cords secured to the inner faces of the side walls adapted to retain the contents of the box member in predetermined position.

6. In a box of the class described, a box member and a cover member, tie cords secured to the outer faces of the walls of said box member adjacent to the upper edge thereof, the attached ends of said cords being concealed by the cover member when mounted upon the box member, and said tie cords being adapted to extend outwardly and around the cover member for securing the cover member in connection with the box member.

7. In a box of the class described, a box member and a cover member, tie cords secured to the outer faces of the walls of said box member adjacent to the upper edge thereof, the attached ends of said cords being concealed by the cover member when mounted upon the box member, said tie cords being adapted to extend outwardly and around the cover member for securing the cover member in connection with the box member, and other tie cords secured to the inner faces of the walls of said box member where said first named cords are attached.

8. In a box of the class described, a box member and cover member, the walls of the cover member overlying predetermined portions of the walls of the box member, tie cords secured in oppositely disposed relations to that portion of the walls of the box member covered by the walls of the cover member, and said strap members extending outwardly and being adapted to be passed around the cover member to retain the same in connection with the box member.

In testimony that I claim the foregoing as my invention I have signed my name this 7th day of June, 1923.

HARRY DERMAN.
